CLAIM

The ornamental design for a handheld wireless reader, as shown and described.

DESCRIPTION

FIG. 1 is a front perspective view of a handheld wireless reader;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference perspective view showing the usage state of the handheld wireless reader of FIG. 1;

FIG. 9 is another reference perspective view showing the usage state of the handheld wireless reader of FIG. 1;
FIG. 10 is a front perspective view of a second embodiment of the handheld wireless reader;
FIG. 11 is a front view thereof;
FIG. 12 is a rear view thereof;
FIG. 13 is a left side view thereof;
FIG. 14 is a right side view thereof;
FIG. 15 is a top view thereof;
FIG. 16 is a bottom view thereof;
FIG. 17 is a reference perspective view showing the usage state of the handheld wireless reader of the second embodiment;
FIG. 18 is another reference perspective view showing the usage state of the handheld wireless reader of the second embodiment;
FIG. 19 is a front perspective view of a third embodiment of the handheld wireless reader;
FIG. 20 is a front view thereof;
FIG. 21 is a rear view thereof;
FIG. 22 is a left side view thereof;
FIG. 23 is a right side view thereof;
FIG. 24 is a top view thereof;

FIG. 25 is a bottom view thereof;
FIG. 26 is a reference perspective view showing the usage state of the handheld wireless reader of the third embodiment;
FIG. 27 is a reference perspective view showing the usage state of the handheld wireless reader of the third embodiment;
FIG. 28 is a front perspective view of a fourth embodiment of the handheld wireless reader;
FIG. 29 is a front view thereof;
FIG. 30 is a rear view thereof;
FIG. 31 is a left side view thereof;
FIG. 32 is a right side view thereof;
FIG. 33 is a top view thereof;
FIG. 34 is a bottom view thereof;
FIG. 35 is a reference perspective view showing the usage state of the handheld wireless reader of the fourth embodiment; and,
FIG. 36 is a reference perspective view showing the usage state of the handheld wireless reader of the fourth embodiment.
Broken lines and portions contained within broken lines are not claimed.
